UNITED STATES PATENT OFFICE.

CHARLES LA DOW, OF ALBANY, NEW YORK.

DESIGN FOR A MOLDING-BED.

SPECIFICATION forming part of Design No. 32,064, dated January 2, 1900.

Application filed November 15, 1899. Serial No. 737,143. Term of patent 14 years.

To all whom it may concern:

Be it known that I, CHARLES LA DOW, of Albany, county of Albany, and State of New York, have invented a new and useful Design for a Molding-Bed, illustrated by the accompanying sheet of drawings and described in the accompanying specification, reference being had to the lines and figures on said drawings.

10 My design relates to molding-beds for plowshares, in which—

Figure 1 is a plan view. Fig. 2 is a sectional view taken through the line y y of Fig. 1. Fig. 3 is a sectional view taken through the line x x of Fig. 1, and Fig. 4 is a plan view of the reverse side of Fig. 1.

The leading features of my design are, first, a plate or bed B, substantially diamond shape in outline, having on one of its surfaces the 20 face of each of two plowshares A A, so outlined on the bed as to present hollows or concaved portions at C C, taken through the line x x in Fig. 1, and also shown at C C in

Fig. 3; second, the aforesaid hollowed portions are bordered by raised portions at c c 25 on each share, taken through the line x x , (shown in Fig. 1, and also shown at c c c in Fig. 3;) third, the narrowest end of the outlined design of each share A A is shown as being at a vertical angle relatively to the 30 horizontal face of the bed B at a b, taken through the line y y in Fig. 1, the part a being higher relatively to bed B than the part b, also shown in Fig. 2; fourth, two plowshares of substantially the shape shown having their back or reverse sides hidden by bed B, on which they rest, and having their face portions hollowed. 35

I claim—

The design for a molding-bed substantially 40 as shown and described.

CHARLES LA DOW.
